UNITED STATES PATENT OFFICE.

FREDERICK G. SCHOLL, OF WOODHAVEN, NEW YORK.

DESIGN FOR A TOY MUSICAL INSTRUMENT.

Application filed March 20, 1925. Serial No. 12,779. Term of patent 7 years.

To all whom it may concern:

Be it known that I, FREDERICK G. SCHOLL, a citizen of the United States, residing at 2083 Jamaica Avenue, Woodhaven, county of Queens, and State of New York, have invented a new, original, and ornamental Design for Toy Musical Instruments, of which the following is a specification, reference being had to the accompanying drawing, forming a part thereof.

The drawing is a perspective view of this toy musical instrument showing my new design.

I claim the ornamental design for a toy musical instrument substantially as shown.

Signed at New York city, county of New York, in the State of New York, this 16th day of March, 1925.

FREDERICK G. SCHOLL.
